UNITED STATES PATENT OFFICE

2,070,710

STEAM DISCHARGE PRESSING DEVICE

Frederick J. Clark, Buffalo, N. Y., assignor to
Steam Pressing Iron Company, Buffalo, N. Y.

Application January 3, 1935, Serial No. 253

10 Claims. (Cl. 38—77)

This invention relates to improvements in pressing irons of that type which are provided with means such, for example, as an electric heating element, for heating the iron and with a steam chamber in which water or wet steam is heated by the iron heating means to furnish steam for discharge at the pressing face of the iron for moistening or steaming the material being pressed.

10 Some goods are spotted or discolored by contact with water and it is therefore important that steam-discharge irons shall be constructed so as to insure that the steam will be in a superheated or dry condition when discharged against the 15 goods being pressed, and so as to prevent the possibility of any wet steam or water issuing from the steam discharge orifices of the iron. Attempts have been made to prevent the possibility of spotting or injuring goods by water in the use 20 of steam discharge pressing irons, by employing irons which are supplied with steam from a distant steam generator or boiler, such irons being provided with means for superheating the steam, and provision being made for preventing any 25 water of condensation from the steam from passing to the steam discharge orifices of the iron. Such irons, however, necessitate an installation including a boiler or generator with flexible steam hose leading to the iron, and other more or less 30 complicated or elaborate equipment, making such irons objectionable or impractical for use in some establishments. Because of such reasons, many 35 users prefer the irons in which the steam is generated in or at the irons themselves from water supplied thereto. An objection to these irons, however, is that the steam generating chambers or passages in the irons become clogged or fouled with lime or other scale or impurities deposited or settling from the water which soon interfere 40 with the efficient or proper operation of the iron unless removed at frequent intervals, and the previous constructions of such irons make it difficult or impractical to properly rid them of the scale or deposits.

45 The objects of my invention are to provide a steam discharging pressing iron in which the steam is generated from the water supplied to the iron but which is of a novel construction which will insure the proper superheating or drying 50 of the steam and prevent the possibility of discharge of any water from the iron; also to construct the iron so that it can be used with either water or steam supplied thereto; also to construct the iron so that the water or steam 55 chambers or bores thereof can be quickly and

easily cleaned out; also to provide a steam generating device which will insure the quick and complete conversion of any water into steam; also to provide desirable steam discharge control means for the device; and also to provide a desirable pressing and steam discharge device which has the other features of improvement and advantage hereinafter described and set forth in the claims.

In the accompanying drawing:

Fig. 1 is a longitudinal, sectional elevation of an electrically heated steam discharge iron embodying my invention.

Fig. 2 is a sectional plan view thereof on line 2—2, Fig. 1.

Fig. 3 is a sectional plan view thereof on line 3—3, Fig. 1.

Fig. 4 is a front elevation of the iron.

Fig. 5 is a detail section, enlarged, of the removable gauze roll and cap for the bore containing the roll.

Figs. 6 and 7 are sections on line 6—6 and 7—7 respectively, Fig. 5.

The preferred embodiment of the invention is illustrated in the drawing in connection with an electric pressing iron of known construction which comprises a bottom plate 10 and a body 11 above the same, both of suitable metal, an electric heating element 12 interposed between the bottom plate 10 and body 11, a cover 13 enclosing the body 11 and heating element, and a handle 14 for the iron carried by arms rising from the cover 13. As shown, the metal body 11 is above and secured to the bottom plate 10 by screws 15 which clamp or secure the electric element 12 between the bottom plate and body 11, and the cover is secured in place by a screw 16 passing through the top of the cover and screwed into a threaded hole in the body 11. 17 represents the terminals or studs for releasably connecting the heating element 12 and electrical conductor, and 18 the usual thermostat arranged in a cavity in the bottom of the iron for controlling the temperature of the iron. The construction of the iron as thus far described is that of a known electrically heated pressing iron. My invention is not concerned with the electrical features of the iron, which may be of the usual and suitable construction, and being well known, further description thereof is unnecessary.

The body 11 of the iron is chambered to receive water for conversion into steam by the heat from the heating element. Preferably, for this purpose, the body 11 is drilled to form two

straight bores 20 and 21 which extend forwardly in the body 11 from its rear end and converge toward and are joined by a chamber 22 in the front portion of the body. This chamber 22 is 5 preferably of circular shape in plan and extends into the body 11 from the upper face thereof, thus being adapted to be readily formed by drilling or boring. The bores 20 and 21 and chamber 22 all 10 communicate and may be considered as different portions of the same chamber. Although the water is admitted to the rear end of the bore 20 and steam is generated in this bore, and passes therefrom through the chamber 22 and bore 21 on its way to the steam discharge orifices in the 15 pressing face of the iron, as presently explained, the two bores 20 and 21 and the chamber 22 are all heated so that the chamber 22 and bore 21 will act to further heat and dry any steam generated in the first bore 20 and also to convert into 20 steam any water which may pass into them from the first bore 20. A top or cover 23 which closes the upper end of the chamber 22, may be removably secured in place as by a nut 24 screwed on the threaded upper end of a stud 25 which is 25 screwed or fixed in a hole in the bottom of the chamber 22 and extends out through a central hole in the cover 23. A suitable packing gasket clamped between the rim of the cover and the shouldered rim of the chamber 22 provides a 30 steam-tight joint between the cover and the chamber 22. If needed, a packing washer can also be placed beneath the nut 24. Water is admitted to the rear end portion of the bore 20 under control of a supply valve 26, hereinafter 35 described, which is connected to a nipple 27 communicating with the bore 20, and is provided with a water inlet fitting 28 adapted for connection with a flexible water supply hose or pipe, not shown.

40 The bottom plate 10 of the iron is provided with steam passages which communicate with the steam chamber in the body 11 of the iron and from one or more of which steam discharge orifices or perforations lead to the bottom or pressing face of the iron. Preferably, as shown, two straight bores 30 extend forwardly in the bottom plate 10 from its rear end and connect with two straight cross bores 31 which extend obliquely into the bottom plate from opposite sides of its 45 pointed front end. In addition, the bottom plate is provided with two straight bores 32 which extend forwardly in the bottom plate from its rear end and connect with oblique cross bores 31, and these two longitudinal bores 32 are jointed by a 50 transverse bore 33 which connects with a vertical taper bushing or nipple 34 extending up through the heating element 12 and connecting at its upper end with a transverse bore 35 in the body 11. Bore 35 intersects or connects with the steam 55 chamber 21 in the body so that steam can pass from the rear portion of the chamber 21 through the passage 35, vertical nipple 34 and bores 33 and 32 in the bottom into the oblique bores 31. Small discharge perforations or orifices 36 extend 60 from the passages 31, and also preferably from the connecting passages 30 through the bottom plate to the pressing face thereof for discharging the steam at the pressing face of the iron.

70 Thus, the passages 20 and 21 in the body of the iron are formed by straight bores extending into the body from its rear end, and the transverse passage 35 is formed by a straight bore extending into the body from one side edge thereof, and likewise the passages in the bottom plate are 75 formed by straight bores extending into the bot-

tom plate from one or another edge of the plate so that all of these passages can be readily drilled in the body or bottom plate. The end of each of the several bores at the rear or side edge of the body or bottom plate may be suitably closed, 5 as by a screw plug or stopper, 37 representing the plugs for closing the outer ends of the several bores in the bottom plate.

The body 11 being located directly above the heating element 12, is effectively heated thereby, 10 and the heat is utilized to convert into steam any water in the bores 20 and 21 and chamber 22 in the body 11, and the bottom plate 10 being arranged directly beneath the heating element, is also heated thereby to the temperature necessary 15 for pressing and also for drying or superheating the steam during its passage through the bores in the bottom plate, so that only dry or superheated steam will issue from the discharge perforations in the bottom plate. 20

In order to more thoroughly and efficiently heat the water and convert it into steam in the bores 20 and 21 and prevent condensation of water from the steam, and also to facilitate the removal from these bores of any scale or sediment deposited from the water and thus prevent the clogging of the bores, a roll or cylinder of wire gauze, preferably made by rolling up fine mesh brass wire gauze into a roll of several turns or layers of the gauze, extends into each of the 30 bores 20 and 21 through its open rear end. Each of these gauze rolls is of a diameter adapting it to be easily inserted into and removed from the bore 20 or 21, and of a length for its outer end to extend beyond the bore into a hollow screw cap 35 or member 40 which closes the outer end of the bore. As shown, this cap screws onto a nipple 41 screwed into the threaded outer end of the bore and through which the gauze roll extends. The screw cap projects outwardly from the rear end 40 of the body of the iron, and the wire gauze roll extends outwardly beyond the end of the body 11 and nipple 41 into the cavity of the cap. Therefore, the screw cap can be readily unscrewed and removed, and when removed, the gauze roll will 45 be left projecting out of the bore beyond the outer end of the nipple, so that the roll can be readily grasped and pulled out of the bore. The gauze roll provides a heat conducting body having an extensive surface area, and when the water is 50 admitted to the bore 20, it will fall on and spread out in thin films on the wires of the gauze and will be prevented by the gauze from lying in drops or pools in the bore. Therefore, the water will be quickly converted into steam in the bore 20 55 or, in case too great a volume of water is admitted to the bore, if any water passes as liquid from the bore 20 into the other bore 21, it will likewise spread out on or over the gauze roll or cylinder in the latter bore, and all of the water will be 60 converted into steam before it passes from the rear end portion of the bore 21 to the distributing bores in the bottom plate of the iron. Furthermore, scale or sediment deposited or settling from the water will collect on one or the other of 65 the gauze rolls, and since these are readily removable, as explained, they can be frequently removed and any scale or sediment thereon easily dislodged by tapping the gauze rolls against an object. The gauze rolls, freed from the scale 70 or sediment, then can be quickly and easily replaced in the iron and their efficiency thus maintained and the accumulation of the scale or sediment in the bores prevented. Because of the facility with which the gauze rolls can be removed 75

and replaced, they can be frequently removed without objectionable labor or loss of time to clean them and the bores, and there is therefore not the probability of the scale or sediment being allowed to accumulate in the bores sufficiently to interfere with the efficient generation of the steam and operation of the iron, as occurs in the use of irons which cannot be so easily cleaned. Also, the gauze rolls will not become cemented in the bores by the accumulation and baking of the scale, as happens in previous constructions, in which somewhat analogous elements have been employed in the steam passages, but in which they are left inaccessible when the passages are opened, so that the elements cannot be readily removed. Because of the greater inconvenience and labor in removing such elements in the prior constructions, they are allowed to remain longer in the irons, often until they become cemented in the passages, thereby making it practically impossible to remove them or, if they can be removed, the use of the implement necessary for the purpose breaks or mutilates the elements so as to render them unfit for reuse. These difficulties are eliminated by the described construction, in which the caps 40, when removed, leave the gauze rolls projecting from the bores so that they can be grasped and pulled out.

The chamber 22 can be readily opened and cleaned out by removing its top cover. Since the steam will be superheated and thoroughly dried in its passage through the bore 20, chamber 22 and bore 21 before entering the steam passages in the bottom plate 10, these will not become fouled and will not require cleaning out under normal conditions. However, should this become necessary, the removable screw plugs afford access to the passages.

The water supply valve 26 is preferably a needle valve having a rotatable screw needle with a conical inner end cooperating with a small hole or seat in the inner end of the valve casing and communicating with the inlet fitting 28 for regulating the flow through the valve. The needle rod 45 of the valve projects out of the valve casing through a suitable packing gland or box and extends forwardly of the iron above the cover 13, and has fixed to its forward end an operating arm or lever 46 which extends upwardly and inwardly toward the front end of the handle 14 of the iron so that the button or knob 47 at the free end of the lever is located in convenient position for operation by the thumb of the hand grasping the handle of the iron to open and close the valve 26.

48 represents a set screw which passes through and turns in a threaded hole in a bracket or part 49 located adjacent the front supporting arm for the handle 14 of the iron. This set screw is located so that its inner end is adapted to be engaged by and serve as an adjustable stop for the actuating lever 46 of the valve. The valve is closed by a downward movement of the lever 46 and opened by an upward movement of the lever, and the opening movement of the lever is limited by engagement of the lever with the set screw 48. Thus, by adjusting the set screw in or out, the opening movement of the valve can be arrested when the valve has been opened to a greater or less extent, thereby regulating, as desired, the amount of water admitted by the valve, each time it is opened, to the steam generating chamber 20 of the iron. Since the valve is closed by movement of its actuating lever 46 downwardly or away from the set screw, and is opened by movement of the lever upwardly or toward the

set screw, the opening movement of the valve is controlled by the adjustment of the set screw, and by first setting the set screw so as to determine the extent to which the valve can be opened, the valve can be quickly opened to such extent 5 simply by moving the lever until it is arrested by the set screw. The valve will always be opened the same amount so long as the adjustment of the set screw remains unchanged, and when the set screw has once been set to determine the extent of opening of the valve, the valve can be quickly opened just this amount without the exercise of care or judgment on the part of the user of the iron, it being simply necessary for him to move the lever until it is arrested by the set screw. 15 In this way the amount of the water delivered to the steam generating chamber, when the valve is opened, can be regulated with precision, as required, and the amount of water delivered will be always uniform whenever the valve is opened. If 20 more or less water is required, this can be effected simply by adjusting the set screw to control the extent of opening of the valve.

As shown, the lug 49 in which the set screw 48 turns projects from a bearing bracket 50 secured 25 to the front arm of the handle 14 of the iron, said lug having a split intersecting the threaded hole for the set screw and a screw 51 by which the split portion of the lug can be drawn together to grip and securely hold the set screw in its adjustments. Preferably, a finger wheel 52 is fixed, as by a nut 53, to the front end of the valve rod 45 and the valve actuating arm 46 is adjustably secured on the hub of the finger wheel, as by clamping the split inner end of the arm on the 35 hub by a screw 54. Thus, the arm 46 can be loosened and the valve adjusted in or out by turning the wheel 52 and the arm again fixed to the wheel. This construction enables the valve to be set, if necessary, so that it will be opened a greater or 40 less amount when arrested by the set screw, and also enables adjustments of the valve to compensate for wear.

While the pressing iron or device constructed, as illustrated in the drawing and hereinbefore 45 described, is especially intended and desirable for use when the steam for discharge at the pressing face is generated in the heating chambers 20, 21 and 22 or in one or another thereof from water in liquid form supplied to the chamber 20, the 50 described construction is also capable of use with steam instead of water supplied to the heating chambers of the device for superheating or drying. Therefore, the device is adapted for use in establishments equipped with steam generating 55 installations.

I claim as my invention:

1. A pressing device comprising a body having a chamber with an opening thereinto, a closure for said opening movable to uncover the opening, 60 means for heating water in said chamber to generate steam, and an element in said chamber for receiving deposits from the water, said element being of a size and positioned in the chamber to project out through said opening when said closure is moved to uncover the opening and being removable from the chamber through said opening.

2. A pressing device comprising a body having a straight passage extending thereinto from one 70 face of the body, a closure for the outer end of said passage movable to open said outer end, means for admitting water to said passage, means for heating the water in said passage to generate steam, and a straight element which occupies 75

- said passage for receiving deposits from the water and is of a length to project out beyond the outer end thereof and is removable through said outer end when opened.
5. 3. A pressing device comprising a body having a steam passage extending thereinto from a face of the body, a closure for the outer end of said passage movable to open said outer end, means for heating said chamber, and a wire gauze element which occupies said passage and is of a length to project out beyond the outer end thereof and is removable through said outer end when the latter is opened.
15. 4. A pressing device comprising a body having a chamber with an opening thereinto, a hollow cap closing said opening and movable to uncover the opening, means for heating water in said chamber to generate steam, and an element which occupies said chamber for receiving deposits from the water and is of a length to project through said opening into the cavity of said hollow cap and is removable from the chamber through said opening when said cap is moved to uncover the opening.
25. 5. A pressing device comprising a body having a straight passage extending thereinto from one face of the body, a hollow cap which closes the outer end of said passage and is movable to open said outer end, means for heating said passage and a wire gauze roll which occupies said passage and is of a length to project beyond the outer end thereof into the cavity of said hollow cap, so that when said cap is moved to open the outer end of the passage the end of the roll will project out of the passage and can be grasped to pull the roll out of the passage.
6. A pressing device comprising a body having communicating straight passages extending thereinto from one end of the body, a closure for the outer end of each passage movable to open said end, means for heating said passages, means for admitting fluid to one of said passages, and means for discharging steam from another of said passages, and a wire gauze element which occupies each passage and is of a length to project out beyond the outer end thereof and is removable through said outer end when the latter is opened.
7. A pressing device comprising a body having two straight passages extending thereinto from one end of the body, a chamber joining the inner ends of said passages to enable circulation from one passage to the other, a top cover for said chamber movable to afford access to the chamber for cleaning it, a closure for the outer end of each passage movable to open said end, means for heating said passages, means for admitting fluid to one of said passages, and means for discharging steam from another of said passages, and a wire gauze element which occupies each
- passage and is removable through said outer end when the latter is opened for removing deposits from the passage.
8. A pressing device comprising a body having two straight passages extending thereinto from one end of the body, a chamber joining the inner ends of said passages to enable circulation from one passage to the other, a removable top cover for said chamber affording access to the chamber for cleaning, a closure for the outer end of each passage movable to open said end for cleaning out the passage, means for heating said passages, means for admitting fluid to one of said passages, straight bores in said device adjacent the pressing face thereof each extending into the device from a face thereof, said bores communicating with each other and with the second of said passages, a plug closing the outer end of each of said bores, and steam discharge orifices leading from one or more of said bores to the pressing face of the device.
9. A pressing device comprising a body and a bottom plate, a heating element between the body and bottom plate for heating both, two straight bores extending into the body from one end thereof, means for admitting fluid to one of said bores, a chamber joining the inner ends of said bores to enable circulation of fluid from said one bore to the second bore, removable closures for the outer ends of said bores whereby the bores can be opened for cleaning them, oblique bores extending into said bottom plate from its side edges, longitudinal bores extending into said bottom plate from its rear end and connecting with said oblique bores, a transverse bore connecting said longitudinal bores and communicating with said second bore in said body, and steam discharge orifices leading from said oblique bores to the face of the bottom plate.
10. A pressing device comprising a body and a bottom plate, a heating element between the body and bottom plate for heating both, two straight bores extending into the body from one end thereof, means for admitting fluid to one of said bores, a chamber joining the inner ends of said bores to enable circulation of fluid from said one bore to the second bore, removable closures for the outer ends of said bores whereby the bores can be opened for cleaning them, oblique bores extending into said bottom plate from its side edges, longitudinal bores extending into said bottom plate from its rear end and connecting with said oblique bores, steam discharge orifices leading from said oblique and longitudinal bores to the face of the bottom plate, a transverse bore in the bottom plate communicating with said second bore in said body, and bores extending longitudinally in the bottom plate from said transverse bore to said oblique bores.

FREDERICK J. CLARK. 60
